UNITED STATES PATENT OFFICE.

FRED EDWARD BIERTUEMPFL, OF NEWARK, NEW JERSEY.

GAME.

1,319,372.

Specification of Letters Patent. Patented Oct. 21, 1919.

Application filed April 1, 1919. Serial No. 286,743.

To all whom it may concern:

Be it known that I, FRED EDWARD BIERTUEMPFL, a citizen of the United States, residing at Newark, in the county of Essex 5 and State of New Jersey, have invented certain new and useful Improvements in Games, of which the following is a specification.

This invention relates to games, and more particularly to a parlor game, in which a 10 game of basketball is simulated.

An object of the invention is to provide a game structure which may be placed upon a table or other analogous support and which includes a plurality of pivotally mounted 15 members adapted, upon downward snapping or pivotal movement thereof, to propel a resilient ball toward either end of the game structure, for forcing it to fall through a loop or basket which operation may be the 20 point of the game.

A further object of this invention, is to provide, in a game as specified, a plurality of ball projecting members pivoted in sets at opposite sides of the supporting board or 25 base of the game, which projecting members have their upper surfaces inclined toward each other to provide trough like recesses to receive the ball to be projected, and also to incline the projecting members, which represent the usual players of the basketball game 30 toward their free ends, and to so shape them that when the ball is projected from one of said free ends, its course will be substantially directed to the basket.

Further, the invention comprehends the provision of a game structure, which when played will simulate the ordinary basketball game and one in which speed, practice and skill are factors as well as a game which will 35 be interesting, and exciting.

Other objects of the invention will appear from the following detailed description, taken in connection with the accompanying drawings, forming a part of this specification, and in which drawings:

Figure 1 is a perspective view of the improved game.

Fig. 2 is a longitudinal section through the game.

Fig. 3 is a side elevation of one of the projecting members showing the supporting base in section.

Fig. 4 is a fragmentary perspective view of a pair of the projecting members, illustrating the manner of forming them to properly retain and project the ball.

Fig. 5 is a detail perspective view illustrating the manner of connecting the parts of the game structure, and

Fig. 6 is a detail perspective view of the 60 basket through which the ball is to be dropped.

Referring more particularly to the drawings, wherein like characters indicate like and corresponding parts throughout the 65 several views, 1 indicates the supporting base of the game structure which is rectangular in shape and may be of any desired size.

The supporting base 1 of the game structure has a pair of transversely extending 70 blocks 2, positioned upon its upper surface, one near each end thereof, and the upstanding end boards 3 of the game housing are hingedly connected to these blocks 2 by means of hinges 4, so as to allow the end 75 pieces to fold downwardly upon the projecting members which are generically indicated by the numeral 5 when the game is not in use.

The basket or loop, through which the 80 ball 6 is projected by the projecting members 5, are preferably formed of wire, bent to form the circular loops 7, the ends of which wires are twisted together as shown at 8 and bent to provide laterally extending 85 portions 9. These laterally extending portions 9 are inserted through the loops or convolutions 10 of the supporting structures 11, of the basket. The supporting structures 11 are made of wire or analogous material 90 and they include a plurality of arms which radiate from the convolutions 10. The ends of the arms 12 of the supports 11 are angled as shown at 14 for removable insertion through the staples 14 carried by the end 95 pieces 3, thus permitting the detachment or disconnection of the basket, from the end pieces, when it is desired to fold the game structure.

Rods 15 are connected to the transverse 100 blocks 2 near their ends and these rods 15 extend in parallel relation, longitudinally of the base 1 and form pivotal supports for the projecting members 5.

These projecting members 5 are preferably 105 constructed of wood or other like material and have brackets 16 attached to their under surfaces near their outer ends, for pivotally mounting them upon the respective rods. For instance, the projecting members 110 5 are arranged in sets, of preferably five each, and the active spaces of the projecting

members of each set are shaped alike, and inclined transversely, toward the edge which faces the basket 7 through which they should project the ball 6. The upper or 5 active spaces of these projecting members 5 also incline toward their free ends, as clearly shown in Fig. 4 of the drawings, and the sets thereof are disposed in opposed relation, forming hollows, into which the ball 6 will 10 roll, and owing to the longitudinal inclining of the active surfaces of the projecting members 5, the ball will roll longitudinally over one or the other of the adjacent opposed projecting members to the lowermost end thereof, and if, when in such position, the operator 15 will strike the striking handle or portion 17 of the said projecting element, the ball 6 will be projected substantially in a direct path to the proper basket for making 20 a count in the game. The striking portions 17 of the projecting elements 5 are flat and formed at one end of the striking elements, the said striking portions of one set projecting in one direction while those of the 25 opposite set of the projecting members or elements extend in the opposite direction, as clearly shown in Fig. 1 of the drawings, thus in playing the game one player would be positioned upon one side of the base 1 and 30 the other player upon the opposite side.

Spiral springs 18 are carried by the base 1 and engage the under surface of the striking portions 17 of the projecting elements 5 for forcing these striking ends upwardly 35 or returning them to their normal positions after they have been moved downwardly, during the playing of the game. Suitable cushions 19 are carried by the base 1 and are adapted to be engaged by the under surface 40 of the free ends of the striking elements when these ends are forced downwardly by the action of the springs 18.

The end boards 3 of the supporting structure of the game have their upper corners 45 beveled as shown at 20 and pins 21 are carried by these beveled corners. The pins 21 are adapted for extension through openings 22 in the ends of the longitudinally extending brace bars 23.

50 A netting 25 is placed over the base 1 and end pieces 3 forming an enclosure to prevent the balls 6 from being projected too great a distance and confining the movement of the balls within the limits of the game structure. This netting 25 is supported, at its ends, by substantially U-shaped supports 26, the ends of which fit in sockets or openings formed in the end blocks 2 as clearly shown 55 in Fig. 1. The legs of these braces 26 are connected near their lower ends by longitudinally extending bars 27 while the netting is placed at the top by the end bracing bars 23.

In playing the game, the ball is first 65 placed in the hollow formed by intermediate

pivoted projecting members which correspond to the centers in a basket ball game, and the players of the game then press downwardly on a pressing or handle portion 17 of these center projecting members, the 70 player passing first starts the ball 6 in motion, and if the ball does not pass through the basket corresponding to the projecting member from which it is projected, it will be returned, by the net structure 26 in the 75 hollow between a pair of projecting members, and one or the other of these projecting members are then depressed depending upon the player who is quickest in action and the ball is thus continued in motion. The rules 80 and counts of the game are the same as those in an ordinary basketball game.

Changes in details may be made without departing from the spirit of this invention, but;

85

I claim:

1. In a game, the combination of a supporting base, a plurality of projecting elements pivotally supported by said base adjacent its side edges, and arranged in sets, 90 the projecting elements of said sets being arranged alternately, the upper surfaces of the projecting elements being inclined transversely and having their lowermost portions facing a companion projecting element of 95 the other set.

2. In a game, the combination, with a resilient ball, of a supporting base, a plurality of projecting elements arranged in sets, the projecting elements of one set being 100 pivoted at one edge of said supporting base, and the edge opposite that adjacent which the projecting elements of the other sets are pivoted.

3. In a game, the combination, with a resilient ball, of a plurality of pivotally supported projecting elements arranged in sets, the projecting elements of one set adapted to project the ball in a direction opposite to its projection by the other set, the projecting elements of said sets being arranged alternately.

4. In a game, the combination, of a supporting base, a resilient ball, a plurality of projecting elements pivotally supported by 115 said base adjacent its side edges and arranged in sets, the projecting elements in one set being positioned adjacent the edge opposite to the edge adjacent which the projecting elements of the other set are pivoted, 120 the projecting elements of said sets being arranged alternately.

5. In a game, the combination, of a supporting base, a resilient ball, a plurality of projecting elements pivotally supported by 125 said base adjacent its side edges and arranged in sets, the projecting elements in one set being positioned adjacent the edge opposite to the edge adjacent which the projecting elements of the other set are pivoted, 130

- the projecting elements of said sets being arranged alternately, the upper surfaces of said projecting elements being inclined transversely, having their lowermost portions facing a companion projecting element of the other set. 5
6. In a game, the combination, of a supporting base, a resilient ball, a plurality of projecting elements pivotally supported by 10 said base adjacent its side edges and arranged in sets, the projecting elements in one set being positioned adjacent the edge opposite to the edge adjacent which the projecting elements of the other set are pivoted, 15 the projecting elements of said sets being arranged alternately, the upper surfaces of said projecting elements being inclined transversely, having their lowermost portions facing a companion projecting element 20 of the other set, said projecting elements also being inclined toward their free ends. 25
7. In a game, the combination of a supporting base, a plurality of projecting elements pivotally supported by said base adjacent its side edges and arranged in sets, the projecting elements of said sets being arranged alternately, the upper surfaces of the projecting elements being inclined transversely and having their lowermost portions 30 facing a companion projecting element of the other set, baskets arranged in spaced relation above the plane of said projecting element, and means carried by said supporting base for limiting the amplitude of movement of the means projected by said projecting element. 35
8. In a game, the combination of a supporting base, a plurality of projecting elements pivotally supported by said base and arranged in sets, the projecting elements of said sets being arranged alternately, the upper surfaces of said projecting elements being inclined transversely and having their lowermost portions facing a companion projecting element of the other set, and means 40 for returning the projecting elements to their normal positions after operation. 45
9. In a game, the combination, of a resilient ball, a plurality of pivotally supported projecting elements arranged in sets, the projecting elements of one set being adapted to project the ball in a direction opposite to its projection by the other set, baskets arranged in spaced relation and 50 adapted to receive the ball upon projection by said projecting elements, said projecting elements of said set being arranged alternately. 55
10. In a game, the combination, of a resilient ball, a plurality of pivotally supported projecting elements arranged in sets, the projecting elements of one set being adapted to project the ball in a direction opposite to its projection by the other set, baskets arranged in spaced relation and 60
- adapted to receive the ball upon projection by said projecting elements, the projecting elements of said set being arranged alternately, means for returning the projecting elements to their normal positions after 70 operation. 75
11. In a game, the combination, of a resilient ball, a plurality of pivotally supported projecting elements arranged in sets, the projecting elements of one set being adapted to project the ball in a direction opposite to its projection by the other set, baskets arranged in spaced relation and adapted to receive the ball upon projection by said projecting elements, the projecting elements 80 of said set being arranged alternately, means for returning the projecting elements to their normal positions after operation, and cushioning means for cushioning the return movement of said projecting elements. 85
12. In a game, the combination, of a supporting base, a resilient ball, a plurality of projecting elements pivotally carried by said base and arranged in sets, the projecting elements of one set adapted to project the ball 90 in a direction opposite to its projection by the other set, baskets arranged in spaced relation above the plane of said projecting elements, the active surfaces of said projecting elements being inclined, to present hollows 95 adapted to receive said ball prior to its projection by the projecting element. 100
13. In a game, the combination, of a supporting base, a resilient ball, a plurality of projecting elements pivotally carried by said base and arranged in sets, the projecting elements of one set adapted to project the ball in a direction opposite to its projection by the other set, baskets arranged in spaced relation above the plane of said projecting elements, the active surfaces of said projecting elements being inclined laterally to present hollows adapted to receive said ball prior 105 to its projection by the projecting element, said projecting elements having their upper surfaces inclined longitudinally to provide receiving portions adapted to receive the ball and from which the ball will be projected for dropping through the corresponding basket. 110
14. In a game, the combination, of a supporting base, a resilient ball, a plurality of projecting elements pivotally carried by said base and arranged in sets, the projecting elements of one set adapted to project the ball 115 in a direction opposite to its projection by the other set, baskets arranged in spaced relation above the plane of said projecting elements, the active surfaces of said projecting elements being inclined laterally, to present hollows adapted to receive said ball prior to its projection by the projecting element, said projecting elements having their upper surfaces inclined longitudinally to provide receiving portions adapted to re- 120
- 125
- 130

ceive the ball and from which the ball will be projected for dropping through the corresponding basket, and a net work inclosing the active portions of said projecting elements and said baskets.

15. In a game, the combination, of a supporting base, a resilient ball, a plurality of projecting elements pivotally carried by said base and arranged in sets, the projecting elements of one set adapted to project the ball in a direction opposite to its projection by the other set, baskets arranged in spaced relation above the plane of said projecting elements, the active surfaces of said projecting elements being inclined laterally, to present hollows adapted to receive said ball prior to its projecting by the projecting element, said projecting elements having their upper surfaces inclined longitudinally to provide receiving portions adapted to receive the ball and from which the ball will be projected for dropping through the corresponding basket, a net work inclosing the active portions of said projecting elements and said baskets, means for returning said projecting elements to their normal positions after operation.

16. In a game, the combination, of a supporting base, a resilient ball, a plurality of projecting elements pivotally carried by said base and arranged in sets, the projecting elements of one set adapted to project the ball in a direction opposite to its projection by the other set, baskets arranged in spaced relation above the plane of said projecting elements, the active surfaces of said projecting elements being inclined, to present hollows adapted to receive said ball prior to its projecting by the projecting element, said

projecting elements having their upper surfaces shaped to provide receiving portions adapted to receive the ball and from which the ball will be projected for dropping through the corresponding basket, a net work inclosing the active portions of said projecting elements and said baskets, means for returning said projecting elements to their normal positions after operation, cushioning strips carried by said supporting means and adapted to cushion the return movement of said projecting elements.

17. In a game, the combination of a supporting base, a plurality of projecting elements pivotally supported by said base and arranged in sets, the projecting elements of said sets being arranged alternately, the upper surfaces of said projecting elements being inclined transversely and having their lowermost portions facing a companion projecting element of the other set, means for returning the projecting elements to their normal positions after operation, and cushioning means for cushioning the return movement of said projecting elements.

18. In a game, the combination, of a plurality of pivotally supported projecting elements arranged in sets, the projecting elements of one set adapted to project an article in a direction opposite to its projection by the other set, the projecting elements of said sets being arranged alternately, means for returning the projecting elements to their normal positions after operation, and cushioning means for cushioning the return movement of the projecting elements to their normal positions.

FRED EDWARD BIERTUEMPFEL.
